LOCK AND LATCH CONSTRUCTION

Herman Hansen, New York, N. Y., assignor to
 Francis Keil & Son, Inc., a corporation of New
 York

Application October 7, 1933, Serial No. 692,556

13 Claims. (Cl. 70—29)

This invention relates to lock and latch construction, particularly to certain constructions of this character employed in heavy-duty service.

One of the objects of this invention is to provide a simple, practical, inexpensive but thoroughly reliable lock and latch construction. Another object is to provide a construction of the above-mentioned character in which a key-control of a latch may be effectively and inexpensively achieved and whereby the latch may be made dependably to function as a dead bolt. Another object is to provide a construction of the above-mentioned character that will be compact, foolproof in construction and action, and simple to control or operate. Another object is to provide a latch construction in which the manufacture and assembly will be inexpensive and yet not detract from dependability of construction and action and durability. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown one of the various possible embodiments of this invention,

Figure 1 is a side elevation, certain parts being broken away, of the lock and latch construction shown as applied in practical use;

Figure 2 is a fragmentary longitudinal central sectional view, on an enlarged scale, showing more clearly certain of the features of construction;

Figure 3 is a horizontal sectional view as seen along the line 3—3 of Figure 2;

Figure 4 is a vertical sectional view as seen along the line 4—4 of Figure 2;

Figure 5 is a fragmentary portion of a view like that of Figure 1 showing a preferred embodiment of certain features, and

Figure 6 is an elevation, as seen from the right in Figure 5 of a locking bolt.

Similar reference characters refer to similar parts throughout the several views of the drawing.

Referring now first to Figure 1, there is shown at 10 a wall having a door-opening therein in which is suitably hinged a door 11. Mounted upon the door 11 is the lock and latch construction and that includes a frame generally indicated at 12, having a base portion 13 suitably

apertured, whereby screws 14, or the like, may be employed to secure the frame 12 to the door.

The right-hand or forward portion of the frame 12 is hollow or housing-like in construction, having a front wall 15 provided with an opening 16, preferably square or rectangular in shape, through which is projectable a latch bolt 17, more clearly described hereinafter. The front wall 15 is bounded at its sides by side walls 18—19 (Figure 4) that extend rearwardly or to the left, terminating in a rear wall 20 (Figure 1). Alined with the opening 16 in the front wall 15 is an opening 21 in the rear wall 20, that opening being preferably round.

The latch bolt 17 is preferably shaped as is shown in Figures 1, 2, and 3, being slotted (see Figure 3) as at 22, thus providing side portions 23 and 24 joined at their forward ends by the active portion of the bolt 17 and joined at their rear ends by a cross-portion 25. Secured to or integrally formed with the rear cross-portion 25 is a rearward extension or rod 26, preferably cylindrical, and extending through the opening 21 in the rear wall 20 (Figure 1), the bolt 17 being thus slidably supported and guided by the walls 15 and 20 (Figure 1).

Interposed between the rear wall 20 and the cross-portion 25 of the bolt 17 and extending about the bolt extension 26 is a helical spring 27 tending always to push the bolt 17 toward the right, as viewed in Figure 1, and hence out of the frame housing 15.

Extending between the side walls 18 and 19 of the frame is a bell crank lever 28 (Figure 1) pivoted to the side walls by means of the pin 29; 35 the long arm 28^a of the lever 28 extends rearwardly or to the left, as viewed in Figure 1, and functions as an operating handle for the control of the latch bolt 17, while the other arm 28^b of the lever 28 extends downwardly into the slot 22 40 of the bolt 17, engaging against the cross-portion 25 of the latter.

Spring 27 acts normally to hold the latch bolt 17 projected outwardly from the frame or housing and acts also to maintain the operating lever 45 28 in its normal position, the position of both the bolt 17 and the lever 18 being limited by the engagement of the arm 28^b (Figure 1) of the lever 28 against a vertical wall portion 30 (Figures 1 and 2) that substantially parallels the front wall 50 15, being bridged across between the side walls 18—19 but terminating just above the bolt 17.

Suitably secured to the frame or wall 10, as by screws, bolts, or the like, indicated at 31, is a keeper or striker 32 suitably shaped, for example 55

as indicated in Figure 1, to coat with the latch bolt 17, the curved face 17^a of the latch bolt 17, together with the yieldability of the spring 27, permitting the latch bolt 17, when the door 11 is swung closed, to by-pass the overhanging part 5 of the keeper 32 and then spring into the recess of the latter, thus holding the door 11 closed.

The side walls 18-19 (Figure 4) and the vertical walls 15 and 30 (Figure 1) form a recess 34, open at the top but closed at the bottom as by 10 the horizontal wall portion 33 (see also Figures 2 and 4). The frame 12 may readily be cast to give it the shape above described in detail, though it may be noted that the recess 34, instead of 15 being cored out, might be bored out or drilled and that conveniently it can be and preferably is of circular horizontal cross-section, its upper peripheral portion being preferably stepped, as at 35, better shown in Figures 2 and 4.

20 The bottom wall portion 33 of the recess 34 is preferably of substantial thickness and in it is formed a vertically extending channel or hole, positioned along the center line of the bolt 17, the hole being threaded as at 36, preferably with 25 a thread of relatively large pitch.

Threaded into the threaded hole 36 is a rotary locking bolt 37 conveniently and preferably given the form of a hollow cylinder, whose upper end wall 37^a is provided with a transverse or diametrically extending slot 37^b.

30 The locking member 37 is adapted to coat with the bolt 17 and more specifically the slot 22 (see Figure 3) in the bolt 17 is of such extent in a direction toward the right, as viewed in Figures 35 3 and 1, that, when the bolt 17 is in normal extended position, as in Figures 1 and 3, the right-hand end wall 38 of the slot 22 (see Figure 3) is substantially in vertical alignment with the right-hand portions of the cylindrical locking bolt 37. 40 Accordingly, if the locking member 37 is thereupon caused to descend, it enters the slot 22 of the bolt 17 and forms an abutment for the wall portion 33 (Figure 3) of the bolt 17, thus precluding withdrawal of the bolt 17.

45 Referring now to Figures 2 and 4, seated in the step 35 of the recess 34 is the escutcheon or front cylindrical plate 40^a of a so-called cylinder lock barrel 40 having at its lower and diametrically opposed portions (see Figure 4) laterally projecting ears 41 and 42 provided with threaded openings. The bottom wall portion 33 of the recess 34 (Figure 4) is provided with suitably countersunk holes 33^a and 33^b adapted respectively to receive screws 43 and 44 whose upper ends 50 are threaded into the threaded ears 41 and 42 respectively, the screws rigidly securing the barrel 40 in place.

55 The barrel 40 carries a rotatable key plug 40^a provided with a key-receiving slot 40^b and the parts 40 and 40^a are provided with suitable co-acting spring-opposed tumbler pins, or the like, whereby, upon the proper key being inserted into the key-receiving opening 40^b the tumbler pins are suitably set or aligned to thereupon permit the 60 rotation of the part 40^a. Preferably these parts are so related and constructed as is now well known in the art, that the insertion of the proper key permits the manual rotation, through the key, of the part 40^a throughout an angle of 360°.

70 Suitably secured to the lower or otherwise rear end of the rotatable part 40^a of the key-controlled mechanism is an operating bar 45 (Figures 2 and 4), partaking of whatever rotation the key gives to the part 40^a. The operating bar 45 extends 75 downwardly through the slot 37^b of the locking

member 37 and extends to a substantial extent downwardly into the interior or hollow portion of the locking member 37.

Accordingly, when the proper key is inserted and the part 40^a rotated, the operating bar 45 rotates the threaded locking member 37 relative to the bottom wall 33, the threaded interengagement of the locking member 37 with the wall portion 33 being such that this rotation causes the locking member 37 to descend and enter into the slot 22 of the bolt 17, with results already above described.

As above noted, the pitch of the thread on the parts 37-33 is preferably relatively large so that the available angle of rotation given the locking member 37 under the control of the key is adequate to project the locking member 37 sufficiently into the recess 22 in the bolt 17 to dependably lock the latter against retrograde movement.

Moreover, I preferably proportion the parts so that, as appears better in Figure 3, the side portions 23 and 24 of the slotted bolt 17 underlie the openings 33^a and 33^b in the bottom wall 33 and hence underlie the screws 43 and 44 which secure the key cylinder and barrel construction above described in place; thus the upper surface of the bolt 17, as viewed in Figure 1, moves in close proximity to the plane of the lower face of the wall portion 33 and, moreover, underneath these securing screws, thus blocking the latter against retrograde movement.

In view of the foregoing, the operation of the lock and latch construction will be clear; it might be noted, however, that, with the locking bolt 37 withdrawn, the door 11 may be slammed shut or otherwise closed, the spring 27 permitting retrograde movement of the latch bolt 17 to by-pass the projecting part of the striker 32 and then causing the bolt 17 to spring into locking or latching position. To open the door, the handle 28^a is grasped and the exertion of the normal pull in the direction of swinging the door 11 open first causes the latch bolt 17 to be withdrawn from the striker or keeper 32, the proportions of the two arms of the lever 28 greatly facilitating this action, whereupon the door 11 may be swung open. If it is desired to lock the door against opening in the manner just described, the key is inserted into the slot 40^b, with the parts in the position shown in Figure 1, and the key then given the appropriate turn, illustratively 360°, thus rotating the locking bolt 37 and causing it to be projected downwardly into the recess 22 in the bolt 17, thus to lock the latter against retrograde movement.

Under certain circumstances it might be desirable or necessary to lock the bolt 27 against being projected outwardly of the casing and in such case I provide a cylindrical recess 46 (Figure 2) in the upper portion of the bolt 17 to the right of the shoulder portion 38, and in line with the downward movement of the bolt-blocking member 37 when the bolt 17 is withdrawn into the casing. Thus, the bolt may be locked against partaking of its normal functions, a feature presenting the advantage of precluding the accidental or intentional locking of a person into a vault, chamber, refrigerator, or the like.

In Figure 5 I have shown fragmentarily a structure like that above described but embodying a preferred form of locking bolt, the structure, and operation of the form of mechanism of Figure 5 being substantially the same as above described, excepting for the following features of construction and action:—

In the arrangement of Figure 5, the hole 36 is not threaded as was the case in Figures 1 and 2, but is bored out or drilled to provide a smooth cylindrical bearing surface in which is rotatably 5 and slidably supported the rotary bolt 137 (see also Figure 6), the bolt 137 being cylindrical and being otherwise constructed, as described above in connection with Figures 1 and 2, to receive the operating bar 45 of the key-controlled mechanism 40 while maintaining connection therewith even though the bolt 137 moves along its axis as well as partaking of rotation.

The cylindrical locking bolt 137 (Figures 5 and 6) is provided with a helical groove or slot 137^a which, in the illustrative embodiment of Figures 5 and 6, extends substantially throughout 360° and hence throughout substantially one turn.

In the right-hand wall 15 of the frame 12 and 20 hence in that face thereof that is closed over or covered by the keeper 32, as is clearly shown in Figure 5, there is threaded a screw 138, preferably countersunk, the screw having at its innermost end a cylindrical stud 138^a dimensioned 25 to be snugly received in the helical groove or slot 137^a in the bolt 137, when the screw 138 is driven home and locked in place, this relation being clearly shown in Figure 5.

The end walls 137^b and 137^c (Figure 6) in 30 which the ends of the helical slot 137^a terminate are, as the bolt 137 is rotated by the key inserted in the key-controlled mechanism 40, therefore given respective paths of movement, such that they come into engagement with the stud 35 138^a of the screw 138 (Figure 5) and thus limit the extent of rotary movement which the bolt 137 may partake of, the parts being, moreover, preferably so proportioned that the bolt 137 may thus be restricted to rotate throughout exactly 40 360°.

However, as the bolt is thus rotated, either to enter the slot 22 of the latch bolt 17 to lock the latter in extended position or to enter the recess 46 thereof to lock the latch bolt in withdrawn position, or as the bolt 137 is rotated, in opposite direction to withdraw the locking bolt 137 from either the slot 22 or the recess 46, the coaction of the cam slot or helical groove 137^a with the fixed stud 138^a (Figure 5) causes the 50 bolt 137 to partake of downward or upward motion along the guiding ways of the hole 36, depending upon the direction of rotation given the connecting bar 45 by the key and related mechanism.

The arrangement of Figures 5 and 6 has the further advantage that, where it is impracticable or undesired to provide or employ a key-controlled mechanism 40 in which the rotation of the key cylinder, when the proper key is inserted, 55 is definitely limited between extremes that permit the insertion or withdrawal of the key, the stud 138^a, in coacting with the end walls 137^b and 137^c of the cam slot 137^a, definitely limits the rotation of the rotary locking bolt 137 and thus 60 also definitely fixes the limits of rotation of both the connecting bar 45 and the rotary key cylinder 40 to limits such that the insertion and withdrawal of the key may be achieved at these respective limits.

In other respects, the operation and other advantages of the construction of Figures 5 and 6 will be clear in view of the detailed description above set forth in connection with Figures 1-4.

It will thus be seen that there has been provided in this invention a lock and latch construction in which the various objects hereinabove set forth, together with many practical advantages are successfully achieved. It will be seen 5 that the construction is strong, durable, and fool-proof in construction and action, and that, aside from achieving a desirable compactness and neatness of appearance, it is of a character that lends itself to inexpensive manufacture and ease 10 and rapidity of installation. Moreover, it will be seen that the construction is well adapted to meet the hard conditions of practical use.

As many possible embodiments may be made of the above invention and as many changes might 15 be made in the embodiment above set forth, it is to be understood that all matter hereinbefore set forth or shown in the accompanying drawing is to be interpreted as illustrative and not in a limiting sense.

I claim:

1. In construction of the character described, in combination, a casing having therein a spring-opposed latch bolt adapted to be projected therefrom to engage a keeper, manually actuatable 25 means operable from the exterior of said casing for withdrawing said bolt, said bolt having a recess therein, and said casing having a fixed member having an opening therein substantially in alignment with the recess in said bolt when 30 the bolt is projected, a rotary locking member rotatably related to said opening, said rotary member and said fixed member having coacting surfaces whereby rotation of said rotary member is accompanied by motion of translation thereof 35 along said opening and, depending upon the direction of rotation, said rotary member is moved into or out of said recess, key-controlled means carried by said casing for controlling the rotation of said locking member, said key-controlled 40 means including a tumbler-carrying key plug which, for insertion or withdrawal of the key, must assume definitely limited rotary positions, and means providing limits for the rotary position of said tumbler-carrying key plug while 45 maintaining effective range of motion of translation of said rotary member to move into or out of said recess.

2. In construction of the character described, in combination, an open bottomed casing having 50 guiding means therein for slidably supporting a bolt, a bolt slidably supported in said guiding means and adapted to be projected out of said casing, a bolt-blocking member, said bolt having two opposed parts between which said member, 55 when the latter is moved into bolt-blocking position, extends; means in said casing movably supporting said blocking member for movement into or out of bolt-blocking position, key-controlled means for controlling the movement of said 60 blocking member, and means operable through the open bottom of said casing for securing said key-controlled means in place, said securing means including two screws extending through two spaced openings covered respectively by said 65 two opposed parts of said bolt, said opposed parts being of sufficient length to cover said openings and hence said two screws throughout the range of sliding movement of said bolt.

3. In construction of the character described, 70 in combination, an open bottomed casing having guiding means therein for slidably supporting a bolt, a bolt slidably supported in said guiding means and adapted to be projected out of said casing, a bolt-blocking member, means in said 75

casing movably supporting said blocking member for movement into or out of bolt-blocking position, key-controlled means for controlling the movement of said blocking member, and means 5 operable through the open bottom of said casing for securing said key-controlled means in place, said securing means being interiorly accessible only upon removal of said bolt.

4. In construction of the character described, 10 in combination, a casing having guiding means therein for slidably supporting a bolt, a bolt slidably supported in said guiding means and adapted to be projected out of said casing, a bolt-blocking member, said bolt having a slot 15 extending longitudinally thereof, means in said casing movably supporting said blocking member for movement into or out of said slot and hence into or out of bolt-blocking position, key-controlled means for controlling the movement of 20 said blocking member, and means operable through the bottom of said casing for securing said key-controlled means in place, said securing means comprising a pair of threaded members spaced in a direction transverse of said bolt and 25 respectively aligned with the two bolt portions to either side of said slot and engaging said key-controlled means interiorly of said casing and extending through an interior portion of the latter that is covered by said two portions to 30 either side of the slot in said bolt.

5. In construction of the character described, 35 in combination, a casing having guiding means therein for slidably supporting a bolt, a bolt slidably supported in said guiding means and adapted to be projected out of said casing, means operable from the exterior of said casing for manually actuating said bolt, a rotary member carried by an interior rigid part, said rigid part and said member having coating surfaces whereby 40 rotation of said rotary member is accompanied by motion of translation thereof, means including two spaced portions with either of which said rotary member may coact as selected whereby movement of said rotary member in one direction 45 relative to either of said spaced portions prevents actuation of said bolt by said manually operable means in either bolt-retracting direction or bolt-projecting direction, depending upon which of said two portions said rotary member 50 is made to coact with and movement in opposite direction permits operation of said bolt by said manual means, and key-controlled means carried by said casing for controlling the rotation of said rotary member.

55 6. In construction of the character described, in combination, a casing having guiding means therein for slidably supporting a bolt, a bolt slidably supported in said guiding means and adapted to be projected out of said casing, key-controlled means carried by said casing and having an operating member rotatable under the control of said key-controlled means, means for locking said bolt against movement and including a rotary member and supporting means for 60 said rotary member adapted to coact therewith so that rotation of said rotary member is accompanied by motion of translation, said supporting means and said rotary member having coating parts to limit the rotation of said rotary member, and a telescopic driving connection between 65 said operating member and said rotary member whereby said key-controlled means rotates said rotary member throughout the range of motion of translation of the latter, said coating parts 70 acting through said driving connection to cor-

respondingly limit the rotation of its operating member commensurately with the requirements of said key-controlled means.

7. In construction of the character described, 5 in combination, a casing having guiding means therein for slidably supporting a bolt, a bolt slidably supported in said guiding means and adapted to be projected through a wall of and hence out of said casing, key-controlled means carried by said casing and having an operating member rotatable 10 under the control of said key-controlled means, means for locking said bolt against movement in either projecting or retracting direction and including a rotary member and supporting means for said rotary member adapted to coact therewith so that rotation of said rotary member is accompanied by motion of translation, said rotary member being hollow and said operating member extending thereto for maintaining driving connection throughout the range of motion of 15 translation of said rotary member, said bolt having two recesses into either of which said rotary member is projectable when given said motion of translation, one of said recesses when said bolt is in projected position, underlying said wall and 20 said wall being of sufficient thickness in the direction of the length of the bolt to prevent exposure extraneously of said casing of said one recess.

8. In construction of the character described, 30 in combination, a casing having guiding means therein for slidably supporting a bolt, a bolt slidably supported in said guiding means and adapted to be projected through an end wall and hence cut of said casing, key-controlled means carried by said casing and having an operating member 35 rotatable under the control of said key-controlled means, means for locking said bolt against movement in bolt-projecting direction and including a rotary member and supporting means for said rotary member adapted to coact therewith so that rotation of said rotary member is accompanied by motion of translation, said supporting means supporting said rotary member adjacent the inside face of said end wall and so that said motion of translation is in a direction toward or away 40 from said bolt, said bolt having a recess into which said rotary member is movable when the bolt is in retracted position and said wall and said recess being proportioned so that said recess, when said bolt is in projected position, extends to the inside 45 of the outer face of said end wall, said rotary member having a transverse slotted wall through which said operating member extends for maintaining operative driving connection with said rotary member throughout the range of motion of 50 translation of the latter.

9. In construction of the character described, 55 in combination, a casing having guiding means therein for slidably supporting a bolt, a bolt slidably supported in said guiding means and adapted to be projected out of said casing, key-controlled means including a tumbler-carrying key plug which, for insertion or withdrawal of the key, must assume definitely limited rotary positions, carried by said casing and having an operating 60 member rotatable under the control of said key-controlled means, means for locking said bolt against movement and including a rotary member and supporting means for said rotary member adapted to coact therewith so that rotation of 65 said rotary member is accompanied by motion of translation, means forming a connection between said rotary member and said operating member, and means acting upon said rotary member for 70 limiting the rotary motion thereof and for thereby 75

limiting the rotary motion of said key plug in accordance with key-inserting or key-withdrawing requirements of the latter.

10. In construction of the character described, 5 in combination, a casing having guiding means therein for slidably supporting a bolt, a bolt slidably supported in said guiding means and adapted to be projected out of said casing, key-controlled means carried by said casing and having an operating member rotatable under the control of said key-controlled means, means for locking said bolt against movement out of projected position or out of withdrawn position and including a rotary member and supporting means for said rotary member adapted to coact therewith so that rotation of said rotary member is accompanied by motion of translation, said bolt having a part positionable, in response to initial movement of said bolt, to either one side or the other, at will, 15 of the path of movement of translation of said rotary member, means forming a connection between said rotary member and said operating member, and means acting upon said rotary member for limiting the motion of translation of said 20 rotary member.

11. In construction of the character described, in combination, a casing having guiding means therein for slidably supporting a bolt, a bolt slidably supported in said guiding means and adapted 25 to be projected out of said casing, key controlled tumbler and key plug means carried by said casing and having an operating member rotatable under the control of said key-controlled means, said tumbler and key plug means requiring a certain definite range of rotation of said key plug 30 means for locking said bolt against movement and including a rotary member and supporting means for said rotary member, said rotary member having a helical groove therein whose axis is substantially coincident with the axis of rotation of said rotary member, said helical groove having stop-means related thereto, and said supporting means having a member co-acting with said groove and said stop means, and means whereby 35 said rotary member is operated by said operating member, thereby also to cause said stop means and said member coacting therewith to define the range of rotation of said key plug to accord with its required range of rotation.

12. In construction of the character described, in combination, a casing having a bolt telescopically related thereto whereby the bolt may be projected out of said casing or drawn into the latter, a bolt-blocking member, said bolt having two recesses whereby said bolt-blocking member and said bolt upon said bolt being appropriately moved, may be telescopically related to each other upon movement of said bolt-blocking member in a direction at an angle to the direction of movement of said bolt by entry of said member selectively into either of said recesses, key-controlled means carried by said casing and having an operating member rotatable under the control of said means, means supporting said bolt-blocking 15 member in said casing and adapted to coact therewith so that rotation of said bolt-blocking member is accompanied by motion of translation in a direction to telescopically relate said bolt-blocking member to said bolt or to remove said 20 bolt-blocking member out of telescopic relation to said bolt, and a telescopic connection between said bolt-blocking member and said key-controlled operating member.

13. In construction of the character described, 25 in combination, a casing having a bolt telescopically related thereto whereby the bolt may be projected out of said casing or drawn into the latter, a bolt-blocking member, said bolt having two recesses whereby said bolt-blocking member and 30 said bolt, upon said bolt being appropriately moved, may be telescopically related to each other upon movement of said bolt-blocking member in a direction at an angle to the direction of movement of said bolt by entry of said member selectively 35 into either of said recesses, key-controlled means carried by said casing and having an operating member rotatable under the control of said means, means supporting said bolt-blocking member in said casing and adapted to coact 40 therewith so that rotation of said bolt-blocking member is accompanied by motion of translation in a direction to telescopically relate said bolt-blocking member to said bolt or to remove said 45 bolt-blocking member out of telescopic relation to said bolt, and a telescopic connection between said bolt-blocking member and said key-controlled operating member.

HERMAN HANSEN.
